MOP

John F. Bagley, Jr., South Hadley, Mass., assignor
to Stanley Home Products, Inc., Westfield,
Mass., a corporation of Massachusetts

Application March 18, 1949, Serial No. 1,479

Term of patent 14 years

(Cl. D9—2)

To all whom it may concern:

Be it known that I, John F. Bagley, Jr., a citizen of the United States, residing at South Hadley, in the county of Hampshire and Commonwealth of Massachusetts, have invented a new, original, and ornamental Design for a Mop, of which the following is a specification, reference being had to the accompanying drawings, forming part hereof.

Fig. 1 is a front elevational view of a mop, showing my new design; and

Fig. 2 is an end elevational view thereof with the top part of the handle broken off for convenience of illustration.

The rear side of the mop is substantially the same as that shown in Fig. 1.

I claim:

The ornamental design for a mop, as shown and described.

JOHN F. BAGLEY, JR.
